METHOD OF CONNECTING CARRIER FREQUENCY TO A DOUBLE CIRCUIT

William E. Pakala, Forest Hills, Pa., assignor to Westinghouse Electric & Manufacturing Company, East Pittsburgh, Pa., a corporation of Pennsylvania

Application February 4, 1939, Serial No. 254,679

6 Claims. (Cl. 177—352)

My invention relates to a particular connection of a carrier line to a double circuit so as to provide a separate, low-loss carrier circuit in the event that one of the double circuits should become inoperative.

An object of my invention is to provide a novel connection from a pair of parallel-connected branch feeder lines to a pair of high frequency conducting coaxial cables so that two separate carrier wave circuits are provided which allows the use of at least one of the carrier circuits in the event that one of the branch lines should break or otherwise become inoperative.

Another object of my invention is to provide a carrier wave transmission system including a pair of circuits, at least one of which is operative in the event that one of the feeder wires becomes inoperative and in which a minimum amount of energy loss is present under such conditions.

Other objects and advantages will become more apparent from a study of the following specification when considered in conjunction with the accompanying drawing which schematically shows a circuit embodying my invention.

Numerals 1 denotes a three-phase power line which feeds a pair of parallel branch lines 2 and 3, one of which acts as an emergency line in the event that the other line becomes inoperative. Across terminals 4 and 5, which are on lines of different phase relationship, are connected, in series, condensers 6 and 7, choke coils 8 and 9, primaries 10 and 11 of two separate and independent transformers A and B and a pair of ground connections 12 and 13 which are metallically connected to a station ground system. A pair of coaxial type cables 14 of substantial length form a carrier for high frequency current which is fed across terminals 4 and 5. Each of the cables comprises a center wire 15 and a substantially cylindrical coaxial sheath 16 separated by insulating materials 17. The cable is shown partly dotted to indicate its substantial length. The secondaries 18 and 19 of the above-mentioned transformers are connected in series across the center wires of the cables at one end of the cables. A connection 20 is provided between the sheaths of both of the cables at the same end thereof to an intermediate point between the secondaries 18 and 19. At the other end of the cables 14, there are provided an electrical transmitter 21 and an electrical receiver 22. The transmitter includes four grid controlled thermionic tubes 23, 24, 25 and 26 and a pair of separate output transformers 27 and 28, the primary terminals of which are connected to the

plates 29 to 32, inclusive, of tubes 23 to 26, inclusive, respectively. Grids 33 and 34 of tubes 23 and 25 are interconnected and likewise grids 35 and 36 of tubes 24 and 26, thus forming a "push-pull" arrangement. A positive source of plate potential denoted as B+ is applied to central points on the primary windings of the output transformers 27 and 28. The receiver 22 comprises a plurality of transformers 37 and 38, a plurality of variable condensers 39, 40, 41 and 42, a grid leak 43 and a pair of thermionic tubes 44 and 45 in circuit relation, as shown in the drawing.

The receiver is fed by two separate input transformers 46 and 47, the primaries and secondaries of which are each connected in series relation, as shown. The primary coils 48 and 49 of the receiver are connected in series relation with respect to the secondaries 50 and 51 of the transmitter. The terminals of the series connected transmitter secondaries 50 and 51 and of the series connected receiver primaries 48 and 49 are connected by means of conductors 52 and 53 to the central wires at the lower end of cables 14. A conductor 54 connects the intermediate points between windings 50 and 51 and between windings 48 and 49, thus forming a third wire which, in turn, is connected by means of conductor 55 to the sheaths of the lower end of cables 14.

The operation of the device is as follows: A high frequency carrier wave is introduced in the carrier circuit between terminals 4 and 5 and is induced in the secondary windings 18 and 19, and is conducted by means of the center wires 15 to the other end of the cable to conductors 52 and 53, thus introducing the carrier wave in the circuit including the series connected windings 50 and 51 and the series connected windings 48 and 49. The above description is for reception of signals. In the case of transmission of signals, the flow of power is from conductors 52 and 53 toward terminals 4 and 5. No current will be conducted through the conductors 54, 55, the sheaths 16 and conductor 20 if the system is balanced. In the event, however, that a break in the line should occur, for example, at point 56, or that the line 3 should otherwise become inoperative, a separate input circuit is established across primary 10 and secondary 18. Conductor 20 and the sheath 16 of the left cable and conductors 54 and 55 now carry the same current at half the total original voltage (one-half total power output) now being introduced solely through the medium of conductors 52 and 54 across windings 48 and 50 only. The circuit in-

volving winding 19, the right-hand cable and the windings 49 and 51, of course, is inoperative and ineffective to carry power. It will thus be seen that the power transmission is half of its initial value. Furthermore, the conductor 54 instead of carrying no current carries the same current as windings 50 and 48. This comprises a highly efficient system as compared with previously used coupling connections in which a break of one line would cause losses up to the neighborhood of 90% and would make the remaining circuit inoperative due to its inability to carry sufficient power.

In previous coupling connections well known in the art, the third wire (i. e., conductor 54) was not used, nor was the connecting sheath used. Instead, the secondary windings 18 and 19 were connected through cables 14 to conductors 52 and 53 only, without the neutral or third wire. Hence, when a break would develop, such as at point 56, this would be equivalent to an open circuit in winding 11, the effect of which is to increase the impedance of winding 19 due to the opening in its magnetically coupled winding 11 to about ten times its normal value; hence greatly reducing the current in the circuit through windings 18 and 19 and in the receiver transformer windings—in fact, so greatly reducing the current that the remaining power would be rendered ineffective to produce signals in the receiver circuit. Likewise, the high impedance of coil 19 made it substantially impossible to transmit sufficiently strong signals in transmitter 21 across the terminals 4 and 5.

It should be noted that the drawing shows a single transmitter and receiver station, it being understood that a similar transmitter and receiver station, or similar transmitter and receiver stations, are connected across other points than terminals 4 and 5 in the same lines throughout the length of lines 2 and 3. It is understood further that any wire of line 2 can be interconnected with any wire of line 3 to form the carrier circuit for the high frequency carrier wave and instead of using two branch lines 2 and 3, there may be any number of similar branch lines. It is understood also that, although coaxial cables 14 are shown, any other equivalent cable may be used for carrying the high frequency carrier wave to and from terminals 4 and 5.

I am, of course, aware that others, particularly after having had the benefit of the teachings of my invention, may devise other devices embodying my invention, and I, therefore, do not wish to be limited to the specific showings made in the drawing and the descriptive disclosure hereinbefore made, but wish to be limited only by the scope of the appended claims and such prior art that may be pertinent.

I claim as my invention:

1. An electrical transmission system comprising a three-phase power line, a pair of three-phase branch lines each comprising three wires and which branch lines are connected in parallel and are fed from said power line, a pair of high frequency carrier lines each comprising a first conductor and a second conductor, a pair of separate transformers, the primaries of which are connected in series across a pair of wires, one from each of said pair of branch lines, a ground connection between the primaries, and the secondaries of which are connected in series across the first corresponding ends of the said second conductors, an electrical device, a second pair of transformers having primaries which

are connected in series across the other corresponding ends of the said second conductors and having secondaries which are connected to said electrical device, a connection which interconnects the intermediate points between the secondaries of said first pair of transformers and the first corresponding ends of the said first conductors, and a connection connecting the intermediate points of the primaries of said second pair of transformers to the other corresponding ends of the said first conductors.

2. An electrical transmission system comprising a three-phase power line, a pair of three-phase branch lines each comprising three wires and which lines are connected in parallel and are fed from said power line, a high frequency carrier line comprising a pair of parallelly disposed coaxial type cables each of which includes a central wire and a substantially cylindrical and coaxial sheath, a pair of separate transformers the primaries of which are connected in series across a pair of wires, one from each of said branch lines, a ground connection between the primaries, and the secondaries of which are connected in series across the ends of the central wires at one end of said pair of cables, a connection from an intermediate point between said secondaries to both ends of said sheaths at said one end of the cables, an electrical device, a second pair of separate transformers the secondaries of said second pair of transformers being connected to said electrical device and the primaries thereof being connected in series across the ends of central wires at the other end of said cables, and a connection between an intermediate point between said last mentioned primaries and both ends of said sheaths at said other end of said cables.

3. An electrical transmission system comprising a three-phase power line, a pair of three-phase branch lines each comprising three wires and which lines are connected in parallel and are fed from said power line, a high frequency carrier line comprising a pair of parallelly disposed coaxial type cables each of which includes a central wire and a substantially cylindrical and coaxial sheath, a pair of separate transformers the primaries of which are connected in series across a pair of wires, one from each of said branch lines of different phase relationship, a ground connection between said primaries, and the secondaries of which are connected in series across the ends of the central wires at one end of said pair of cables, a connection from an intermediate point between said secondaries to both ends of said sheaths at said one end of the cables, an electrical receiving device, a second pair of separate transformers the secondaries of said second pair of transformers being connected to said electrical receiving device and the primaries thereof being connected in series across the ends of the central wires at the other end of said cables, and a connection between an intermediate point between said last mentioned primaries and both ends of said sheaths at said other end of said cables.

4. An electrical transmission system comprising a three-wire three-phase power line, a pair of three-phase branch lines each comprising three wires and which lines are connected in parallel and are fed from said power line, a high frequency carrier line comprising a pair of parallelly disposed coaxial type cables each of which includes a central wire and a substantially cylindrical and coaxial sheath, a pair of sepa-

rate transformers the primaries of which are connected in series across a pair of wires, one from each of said branch lines, a ground connection between said primaries, and the secondaries of which are connected in series across the ends of the central wires at one end of said pair of cables, a connection from an intermediate point between said secondaries to both ends of said sheaths at said one end of the cables, an electrical receiving device, a second pair of separate transformers the secondaries of said second pair of transformers being connected to said electrical receiving device and the primaries thereof being connected in series across the ends of the central wires at the other end of said cables, an electrical transmitter device having separate output transformers, the primaries of which are connected to said transmitter and the secondaries of which are connected in series and across the ends of the central wires at said other end of said cables, a connection between the intermediate points of the secondaries of said transmitter device, the primaries of said receiver device and both ends of the sheaths of said other end of said cables.

5. An electrical transmission system comprising a three-wire three-phase power line, a pair of three-phase branch lines each comprising three wires and which lines are connected in parallel and are fed from said power line, a high frequency carrier line comprising a pair of parallelly disposed coaxial type cables each of which includes a central wire and a substantially cylindrical and coaxial sheath, a pair of separate transformers the primaries of which are connected between them in series with a ground connection and with a pair of condensers across a pair of wires, one from each of said branch lines, and the secondaries of which are connected in series across the ends of the central wires at one end of said pair of cables, a connection from an intermediate point between said secondaries to both of said sheaths at said one end of the cables, an electrical receiving device, a second pair of separate transformers the secondaries of said second pair of transformers being connected to said electrical receiving device and the primaries thereof being connected in series across the ends of the central wires of the other end of said cables, an electrical transmitter device having separate output transformers, the primaries of which are connected to said transmitter and the secondaries of which are connected in series and across the ends of the central wires of said other end of said cables, a connection between the intermediate points of the secondaries of said transmitter device, the primaries of said receiver device and both ends of the sheaths of said other end of said cables, said transmitter device including four grid-controlled thermionic tubes, each of which includes a cathode, grid and plate, and the plates of which tubes are connected to the four primary terminals of said output transformers, the grids of each pair of thermionic tubes whose plates are connected to different primaries of said transmitter being interconnected.

formers, the primaries of which are connected to said transmitter and the secondaries of which are connected in series and across the ends of the central wires at said other end of said cables, a connection between the intermediate points of the secondaries of said transmitter device, the primaries of said receiver device and both ends of the sheaths of said other end of said cables.

6. An electrical transmission system comprising a three-wire three-phase power line, a pair of three-phase branch lines each comprising three wires and which lines are connected in parallel and are fed from said power line, a high frequency carrier line comprising a pair of parallelly disposed coaxial type cables each of which includes a central wire and a substantially cylindrical and coaxial sheath, a pair of separate transformers the primaries of which are connected in series across a pair of wires, one from each of said branch lines, a ground connection between the primary windings, and the secondaries of which are connected in series across the ends of the central wires at one end of said pair of cables, a connection from an intermediate point between said secondaries to both ends of said sheaths at said one end of the cables, an electrical receiving device, a second pair of separate transformers the secondaries of said second pair of transformers being connected to said electrical receiving device and the primaries thereof being connected in series across the ends of the central wires of the other end of said cables, an electrical transmitter device having separate output transformers, the primaries of which are connected to said transmitter and the secondaries of which are connected in series and across the ends of the central wires of said other end of said cables, a connection between the intermediate points of the secondaries of said transmitter device, the primaries of said receiver device and both ends of the sheaths of said other end of said cables, said transmitter device including four grid-controlled thermionic tubes, each of which includes a cathode, grid and plate, and the plates of which tubes are connected to the four primary terminals of said output transformers, the grids of each pair of thermionic tubes whose plates are connected to different primaries of said transmitter being interconnected.

WILLIAM E. PAKALA.
